UNITED STATES PATENT OFFICE.

ORMAND CLINTON LILES, OF GOLDSBORO, NORTH CAROLINA.

BED-LIFTER.

1,334,914.

Specification of Letters Patent. Patented Mar. 23, 1920.

Application filed May 24, 1919. Serial No. 299,436.

To all whom it may concern:

Be it known that I, ORMAND C. LILES, a citizen of the United States, residing at Goldsboro, in the county of Wayne and State of North Carolina, have invented new and useful Improvements in Bed-Lifters, of which the following is a specification.

The present invention has reference to means for lifting and suspending a wagon bed from the frame thereof, and the primary object of the invention is to produce a device of this character which shall be of a simple construction, strong and durable, and thoroughly efficient for performing its functions.

A further object of the invention is to produce a wagon bed lifter which is in the nature of a collapsible trestle so that the same may be easily transported or stored, the parts thereof being readily set up and effectively held in operative position, while the lifting device connected with the trestle is of a simple, durable and easily operated construction.

Other objects and advantages will present themselves as the nature of the invention is better understood, reference being had to the accompanying drawings, in which:

Figure 1 is a view showing the device in operative position.

Fig. 2 is a top plan view thereof.

Fig. 3 is an end view thereof.

Fig. 4 is a sectional view approximately on the line 4—4 of Fig. 1.

Fig. 5 is a perspective view of the device in its collapsed position.

As illustrated by the drawings, my improvement is in the nature of a collapsible trestle, comprising a horizontal beam 10 and legs 11 which have one of their ends pivotally secured to the sides of the beam at the ends thereof. One pivot may connect each oppositely disposed pair of legs, the said pivots being preferably in the nature of bolts 12 which are engaged by nuts 13, and by screwing the nuts on the bolts the proper frictional engagement between the legs and beams may be obtained. In addition to this, the tightening of the nuts on the bolts permits of the legs being held against the sides of the beam when the device is in collapsed condition. The pivoted ends of the legs 11 are beveled as at 14 and these beveled portions snugly engage with the sides of the beam when the legs are set

up. The legs are retained at a desired outward angle with respect to the ends of the beam by contact with studs 15 which extend laterally from the sides of the beam. The legs are further sustained in their set up position by pivotally connecting to one of each pair of legs a brace 16 that is provided with a notch 17 designed to engage with the stud 18 on the opposite leg.

The beam 10 is centrally provided with a vertically disposed elongated slot 19, and passing through this slot is a link 20. The link 20 passes through an opening 21 in a head piece 22 and is pivotally secured to the said head piece. The head piece is of a length approximately equaling that of the wagon body 23 and has depending from its sides, adjacent to its corners flexible elements 24 having their outer ends provided with hooks 25 that are designed to engage with the under edges of the body of the wagon.

On the beam 10, to one side of the link opening 19 therein there arises a lug 26. The outer end of this lug is preferably bifurcated, and in the said bifurcation is an operating lever 27, the latter being pivoted to the lug as at 28 and being likewise pivoted to the link as at 29. The outer end of the lever has suspended therefrom a chain 30, and one of the links of this chain is designed to engage with the lug 31 on one of the ends of the beam 10. By this arrangement it will be noted that when pressure is exerted upon the free end of the lever and the head piece raised to elevate the wagon body the said head piece may be retained at a desired elevation, which permits of the running gear of the wagon being drawn outward from beneath the body, and the said body sustained in its elevated position for any desired length of time. The body may be readily lowered on the running gear as will, it is thought, be fully understood. When the device is not in use the same is collapsed by releasing the brace members from the legs and folding the legs against the sides of the beams 10. The chain 30 is arranged to have another of its links engage with the leg 31 so as to hold the lever substantially parallel to the longitudinal plane of the beam 10.

It is thought, from the foregoing description, when taken in connection with the drawings, the simplicity of the construction and the advantages thereof will be readily

apparent without further detailed description.

Having thus described the invention, what is claimed as new, is:—

- 5 In a device for the purpose set forth, a trestle comprising a beam having legs pivotally secured thereon, stop means for limiting the outward swinging of the legs with respect to the beam, binding means
10 for holding the legs against the beam, brace means between the respective pairs of legs,

a head piece below the beam, a link pivotally secured to the leg piece and passing through an opening in the beam, a lug on the beam, a lever pivotally secured thereto and pivotally connected to the link, and flexible means between the link and beam for sustaining the lever at various angles with respect to the beam.

In testimony whereof I affix my signature. 20

ORMAND CLINTON LILES.
